UNITED STATES PATENT OFFICE.

JACOB S. BIRNZWEIG, OF NEW YORK, N. Y.

BUTTON.

1,262,166.

Specification of Letters Patent. Patented Apr. 9, 1918.

Application filed November 6, 1917. Serial No. 200,503.

To all whom it may concern:

Be it known that I, JACOB S. BIRNZWEIG, a citizen of the United States of America, residing at New York city, county and State 5 of New York, have invented certain new and useful Improvements in Buttons, of which the following is a full, clear, and exact description.

This invention relates to improvements in 10 buttons, the object being to provide an inexpensive button consisting partly of metal and partly of leather, imitation-leather or even fabric, and so constructed that an embossed design or emblem will keep its shape 15 during wear notwithstanding that the facing or top surface of the button is not made of metal, such embossed buttons heretofore having, so far as I am aware, been made with metal facings or tops. With my improvement I can produce buttons for uniforms or military purposes with the saving 20 of the metal which is usually employed as the facing of such buttons, and furthermore, a button constructed in accordance with my 25 improvement can be manufactured more cheaply than a button made entirely of metal, and besides, the embossed upper surface of my non-metal facing for the button will not be subject to corrosion, as is frequently the case with metal buttons.

I will now proceed to describe my invention more in detail, the novel features of which I will point out in the appended 35 claims, reference being had to the accompanying drawing, forming part hereof, wherein—

Figure 1 is an enlarged sectional view of a button constructed in accordance with my invention;

Fig. 2 is a plan view thereof; and

Fig. 3 is an enlarged sectional view of the ornamental embossed facing or covering for the button and its backing-member.

My improved button consists of a shell-like member 4, an inserted shell-like cap-member 5, an ornamental facing 6, and a backing therefor, indicated by 7. An eye to secure the button to a garment is indicated by 8.

One of the main features of my improved button is the facing 6, which is preferably made of leather or leatheroid, but I do not limit myself to this particular material, as any fabric, other than metal, that can be 55 embossed, will serve for the facing member 6.

As the said facing 6 is preferably embossed, I utilize in connection therewith the backing element 7, which may be made of cardboard or the like, in fact, said backing 60 is preferably made of cardboard or similar stiffening material. Without the backing element 7 the facing 6 could not be embossed so as to retain its embossed design; the backing serves to maintain the said embossing, 65 as the facing 6 will be made out of relatively thin material, such as a treated fabric known as leatheroid. As far as I am aware, I am the first to produce a button having a fabric facing which is embossed and a means 70 to maintain the embossing or back it up so that it cannot be flattened or destroyed by pressure from without.

As can be seen in Fig. 1, the edge of the facing 6 is caught between the flanges of the button members 4 and 5. The facing will be applied during the assembling of the members 4 and 5. The embossing of the facing is indicated by 9. Any design may be employed, the raised portion indicated by 80 9 being representative of a design of any sort.

The backing 7 will be preferably cemented or otherwise secured to the inner surface of the facing 6.

It will of course be understood that the backing 7 will be applied to the facing before the embossing is done.

Of course it will be obvious that the members 4 and 5 may be secured together in any 90 suitable manner other than in the particular way shown in the drawing.

What I claim as my invention is:

1. A button consisting of a shell-like base member, a shell-like cap-member adapted to 95 be forced into the base member, a facing for said cap-member, the edge of said facing being held between the flanges of the base and cap-members, and a backing for said facing, located between the cap member and 100 said facing.

2. A button consisting of a shell-like base-member, a shell-like cap-member, a facing for said cap-member, the edge of said facing being held between the flanges of the base and cap-members and a backing for said facing located between the cap-member and 105 said facing.

3. A button comprising two members a flexible and embossed facing in one piece 110 covering the whole front of the button and a backing of relatively stiffer material held

against the rear face of said facing to maintain the embossing.

4. A button comprising two members an embossed facing of fabric in one piece covering the entire front of the button and additional means for maintaining the embossing.

5. A button having an embossed fabric facing and a backing of cardboard or equivalent non-metallic relatively rigid material for maintaining the embossing said facing and said backing being each in one piece and covering the entire front of the button.

10 6. A button having an embossed fabric facing in one piece covering the entire front of the button and means for maintaining the embossing.

15 7. A button having an embossed fabric

facing in one piece covering the entire front of the button, a backing therefor of relatively stiffer material for maintaining the 20 embossing and a more rigid member behind said backing.

8. A button having a facing of embossed fabric a backing of stiffer material for maintaining the embossing, and still more 25 rigid material behind this stiffer material holding the said backing against the said facing.

Signed at New York city, N. Y. this 3 day of November, 1917.

JACOB S. BIRNZWEIG.
